Primary Examiner — Sanjeev Paul

(74) *Attorney, Agent, or Firm* — Vladimir Postnikov

(57) **CLAIM**

The ornamental design for a drainable back and seat cushion, as shown and described.

DESCRIPTION

FIG. 1 is a perspective view of a drainable back and seat cushion showing the new design;

FIG. 2 is another perspective view thereof;

FIG. 3 is yet another perspective view thereof;

FIG. 4 is a front elevation view thereof;

FIG. 5 is a back elevation view thereof;

FIG. 6 is a left-side view thereof;

FIG. 7 is a right-side view thereof;

FIG. 8 is a top plan view thereof;

FIG. 9 is a bottom plan view thereof;

FIG. 10 is an enlarged view of the encircled portion in FIG. 2;

FIG. 11 is an enlarged view of the encircled portion in FIG. 3;

FIG. 12 is an enlarged view of the encircled portion in FIG. 3;

FIG. 13 is an enlarged view of the encircled portion in FIG. 5;

FIG. 14 is an enlarged view of the encircled portion in FIG. 9;

FIG. 15 is a perspective view of a secondary embodiment of the drainable back and seat cushion;

FIG. 16 is another perspective view thereof;

FIG. 17 is another perspective view thereof;

FIG. 18 is a front elevation view thereof;

FIG. 19 is a back elevation view thereof;

FIG. 20 is a left-side view thereof;

FIG. 21 is a right-side view thereof;

FIG. 22 is a top plan view thereof;

FIG. 23 is a bottom plan view thereof;

FIG. 24 is an enlarged view of the encircled portion in FIG. 16;

FIG. 25 is an enlarged view of the encircled portion in FIG. 17;

FIG. 26 is an enlarged view of the encircled portion in FIG. 17;

FIG. 27 is an enlarged view of the encircled portion in FIG. 19; and,

FIG. 28 is an enlarged view of the encircled portion in FIG. 23.

(Continued)

The dashed lines in FIGS. 2, 3, 5, 9, 10, 11, 12, 13, 14, 16, 17, 19, 23, 24, 25, 26, 27, and 28 represent boundary lines and form no part of the claimed design.

1 Claim, 28 Drawing Sheets
